BURCHARD E. HORNE, OF ANDOVER, MASSACHUSETTS

ROOF COVERING

Application filed June 25, 1926. Serial No. 118,410.

This invention relates to roofs on which are laid shingles, especially of the asbestos or composition type, and to the method of laying the shingles on the roof. It might be used with metal or wooden shingles.

For reasons of ornamentation and economy of material, there is a type of shingle which is substantially of rectangular or diamond form, which it is desirable to lay with one of its points upward.

For convenience in reference, I will call the two substantially straight edges of the shingle which adjoin and come together at a junction, which when a shingle is laid is at the top, the top adjoining edges, and the two adjoining edges which come together at a junction at the bottom, the bottom adjoining edges. I will refer to the upper left and the lower right edges as opposite, and the upper right and the lower left as opposite edges. I will also refer to the junctions of the left top and bottom edges, as the left junction, and the junction of the right top and right bottom edges, as the right junction.

In laying these shingles, those in each course are laid with the right junction of one shingle adjoining the left junction of the shingle on the right and so on, these junction points being in a line parallel with the ridge, and parallel with the courses of shingles.

The next upper course is so laid that its lower junction point is a short distance vertically below the junction points of the right and left shingles so that its lower right edge overlaps almost all of the upper left edge of the shingle to the right in the next lower course, and its lower left edge substantially overlaps the upper right edge of the shingle to the left in such lower course.

It has been found very difficult to lay shingles in this way with accuracy and speed as they cannot be rested on a straight edge as would be the case if they were laid with their lower ends or edges in line like wooden shingles parallel to eaves and ridge.

I have therefore devised a system of marks to be applied to each shingle whereby when the lowest course is accurately laid, the shingles of the succeeding upper courses can

be accurately put in position and attached without the use of straight edges or chalk lines.

As the use of my device does not require any bending of the material, I can use a very stiff or thick shingle and one which does not need to be especially fastened at the bottom.

In the drawings, Fig. 1 is what might be called either a plan or elevation as it shows shingles provided with my invention laid on a roof, viewed at right angles to such roof

Fig. 2 shows a view similar to Fig. 1, with still another alternative method of marking.

Fig. 3 is still another view of another method of marking.

Fig. 4 shows still another method of marking.

In the drawings, M represents a roof and in Fig. 1, A¹, A², A³, A⁴, represent the successive courses of shingles from the bottom upward.

Each shingle has the two adjoining bottom edges 1 and 2 and the top adjoining edges 3 and 4.

Near the bottom end of each top left edge 3 is a mark 5, and near the bottom end of each top right edge 4 is a mark 6.

When the first or lowest course A¹ is laid correctly, the shingles in the next upper course A² are so laid that the mark 6 near the lower end of upper right edge 4 will register with the edge 3 of the adjoining shingle A¹ in the next lower course, while the mark 5 near the lower end of the upper left edge 3 of a shingle A² will register with the upper right edge 4 of the shingle A¹ in the next lower course.

As shown in Fig. 2, instead of the marks being near the lower ends of the top adjoining edges, they may be near the upper end of the lower adjoining edges.

In all cases however the corresponding marks on adjoining edges should be at equal distances from the junction of the two top edges.

In practice it has been found that a convenient way of marking is by cutting a narrow slot through the shingle, and it is obvious that the cut itself is covered by the next higher course.

This is a great advantage as there is a tendency for the edge of the slot to curl.

In Fig. 3, I show a series of shingles C^1 , C^2 , C^3 , C^4 , arranged in courses, each shingle having marks similar to those shown in Fig. 1.

The lower adjoining edges are indicated by 51 and 52, and the upper adjoining edges by 53 and 54.

The marks near the lower ends of the top edges are 55 and 56, and those near the upper ends of the lower edges are 57 and 58.

As shown in Fig. 4, instead of having marks such as shown in Fig. 3, I may use two marks on each top edge of each shingle F.

The bottom edges are indicated by 61 and 62, and the top edges by 63 and 64, and the two top marks on each top edge are indicated by 67 and 68, and the two bottom marks of each top edge are indicated by 65 and 66.

It is obvious that with the construction shown in Figs. 3 and 4 the alinement of the shingles in each upper course can be more accurately made than where there is only a single mark on each adjoining edge.

I may also use as a development of the type shown in Fig. 4, angular marks as indicated in Fig. 5 at 85 and 86, and 87 and 88. The shingles of each course are indicated by P^1 , and P^2 , P^3 , P^4 . The marks adjoin the top and bottom ends of each top edge, and preferably extend inward, then turn at an angle to further assist in correctly locating a shingle in the next upper course. The bottom edges are indicated by 81 and 82, and the top edges by 83 and 84. With this type of mark a slot or cut is not desirable but a groove or painted line can be used to advantage.

For marking, I may use slots, grooves, creases, holes, painted or scratched lines or in fact any clean cut distinguishing device.

I claim:

1. A roof comprising a plurality of horizontal courses of flat flexible fiber shingles so arranged that the shingles of successive courses partly overlie the upper edges of the next lower course, each of said shingles being flat and having its top adjoining edges extending from their junction at equal angles with the courses of shingles, and each shingle having two marks on each side which are equally distant from said junction and are in a line parallel with the courses, each of said marks registering with the adjacent edge of a shingle in an adjoining course.

2. A roof comprising a plurality of horizontal courses of flat flexible fiber shingles so arranged that the shingles of successive courses partly overlie the upper edges of the next lower course, each of said shingles being flat and having its top adjoining edges extending from their junction at equal angles with the courses of shingles, and each shingle having two marks on each side which are equally distant from said junction, each of

said marks registering with the adjacent edge of a shingle in an adjoining course.

3. A roof comprising a plurality of horizontal courses of flat flexible fiber shingles so arranged that the shingles of successive courses partly overlie the upper edges of the next lower course, each of said shingles being flat and having its top adjoining edges extending from their junction at equal angles with the courses of shingles, and each shingle having marks on each side which are equally distant from said junction, each of said marks registering with the adjacent edge of a shingle in an adjoining course.
